UNITED STATES PATENT OFFICE.

STANLEY D. LIVINGSTON, OF NEW YORK, N. Y., ASSIGNOR TO EISEMANN MAGNETO CORPORATION, OF BROOKLYN, NEW YORK, A CORPORATION OF NEW YORK.

SOCKET FOR VACUUM TUBES.

Application filed December 21, 1922. Serial No. 608,214.

To all whom it may concern:

Be it known that I, STANLEY D. LIVINGSTON, a citizen of the United States, and a resident of the city of New York, borough of Richmond, county of Richmond, and State of New York, have invented certain new and useful Improvements in Sockets for Vacuum Tubes, of which the following is a specification.

10 My invention relates to sockets for connecting vacuum tubes in radio circuits, and its object is to provide a socket of simple construction in which positive contact with the terminal pins of a vacuum tube is insured at all times.

15 In vacuum-tube sockets heretofore constructed, the contacts are in the form of separate strips of spring metal, each secured at its end to the base of the socket by a screw and having its free or inner end extending in position to be engaged by the terminal pins of a vacuum tube. In this engagement with the vacuum-tube pins, the contact strips of the socket are bent down. 20 Now, the pins in some tubes are longer than in others, and the longer pins bend the socket contacts down farther. As these socket contacts are thin separate strips, this bending soon impairs their resiliency and 25 after a while they do not spring back to normal position upon removal of the tube. It was found, for instance, that after using a vacuum tube with relatively long terminal pins, a tube with shorter pins would fail to engage the contacts of the socket.

30 It is the purpose of my invention to eliminate the foregoing difficulty by providing a socket in which the contacts are carried by a resilient support of such construction as to insure the correct position of the contacts at all times. In the preferred embodiment of my invention, the resilient support for the contacts is a one-piece circular spring of tempered steel having inwardly projecting prongs which carry the insulated contacts in position to be engaged by the terminal pins of a vacuum tube. The resilient strength of the spring is such that the return of the socket contacts to normal position on removal of the lamp is at all times certain and positive, irrespective of the length of the terminal pins on the lamp.

35 In addition to a resilient support for the contacts, as mentioned, my new socket contains certain improved features of construc-

tion which will become clear as the specification proceeds. The accompanying drawings show a form of socket as used, and I shall describe that construction as a preferred embodiment of my invention. In 60 these drawings,

Figure 1 shows a side elevation of my new socket in full size, with a vacuum tube in position thereon;

Fig. 2 is an enlarged top plan view of 65 the socket shown in Fig. 1, the dimensions being approximately double the actual size for the sake of clearness;

Fig. 3 is a bottom plan view of the socket, showing the same enlargement as Fig. 2; 70

Fig. 4 is an enlarged vertical cross-section approximately on line 4-4 of Fig. 1, showing how the terminal pins of a vacuum tube engage the spring contacts of the socket;

Fig. 5 is a fragmentary view in cross-section approximately on line 5-5 of Fig. 2, showing one of the socket terminals in normal position;

Fig. 6 is a view similar to Fig. 5, showing how one of the socket contacts is depressed by a terminal pin of a vacuum tube; 80

Fig. 7 illustrates a preferred form of spring for mounting the socket contacts.

The vacuum-tube socket of my invention 85 comprises a base indicated as a whole by B, and a tubular shell indicated as a whole by S. These parts may be made of any suitable material, but I prefer to construct them of sheet metal, such as steel, brass, aluminum, or the like. The shell S is of a size to accommodate snugly the cylindrical base portion A of a vacuum tube T. As this tube forms no part of my invention and as such tubes or lamps are well known in the radio art, I need not go into the structural details thereof. I need only say that from the bottom of the lamp extend four terminal pins a, two of which are shown in Fig. 4. As is well understood, these terminal pins 100 lead to the filament, the plate and the grid of the tube. The base portion A of the vacuum tube has a lug 1 adapted to enter a bayonet slot 2 in shell S for securing the tube correctly in position on the socket. 105

The socket base B, which is usually made rectangular, is formed with a peripheral flange 3, having openings or cutaway portions 4 at the corners. The four sides of the flange form a shallow recess in the base. In 110

opposite sides of flange 3 are screw holes 5, which are used when it is desired to screw the socket in an upright position on a vertical panel in a radio set. The top of base 5 B has a pair of holes 6 for receiving screws or other fastening devices to screw the socket on a table. Thus, the socket is equally well adapted for mounting on a table or on a vertical panel

10 The top of socket base B has a central opening 7 of approximately the same diameter as shell S, which is secured to the base in alignment with said opening. For this purpose the base B is provided with inwardly extending lugs 8 and the lower edge of shell S is formed with correspondingly arranged lugs 9. Rivets 10 pass through openings in the aligned lugs 8 and 9 and rigidly connect the shell and the base together. I
15 have shown four pairs of lugs 8 and 9, but the precise number of lugs is not material.

At the bottom of shell S is mounted a circular steel spring 11, which has four inwardly projecting prongs 12. I prefer to secure 20 the spring 11 in position by placing it between lugs 8 and 9, as illustrated in Fig. 4. The spring has holes 13 for the rivets 10. Thus it is clear that the rivets 10 perform the double function of securing shell S to base B and at the same time fastening the spring 11 in the socket. Of course, in the broader aspect of my invention, spring 11 may be held in position by other means, but I prefer the arrangement which I have just 25 described on account of its simplicity. It will be seen from Figs. 2 and 3 that the prongs 12 of the spring are approximately midway of the rivets 10, so that each prong is in effect supported by an arc-shaped 30 spring base extending from one rivet 10 to the other. This spring base, which is a curved blade in the particular construction illustrated, constitutes a torsional spring of sufficient strength and resiliency. Normally 35 the prongs 12 extend slightly upwardly, as shown in Fig. 5. When the prongs 12 are depressed by the contact pins of a lamp, the free portions of the spring 11, by which I mean the portions between the fastening 40 points or rivets 10, are slightly bent or twisted transversely against the normal set of the circular band 11 which in this instance constitutes the spring. Hence, I may 45 properly call this a torsional spring. It is this strong resilient support or base for each prong that permits depression of the prongs to varying degrees and insures the return of 50 the depressed prongs to normal position.

On prongs 12 of the circular spring 11 55 are four socket contacts 14, 15, 16 and 17. These contacts may conveniently be in the form of copper rivets, which are good conducting material and are easily secured in position. These contacts pass through openings 18 in the spring prongs 12 and are each

insulated by washers 19 and 20, one of which is formed with a bushing 21, as shown in Figs. 5 and 6. These washers may be fiber, bakelite, or any other good insulating material. At the bottom of each prong 12 is secured a metal clip 22, which is electrically connected to the associated socket contact but is insulated by washer 20 from the spring 11 and the metallic body of the socket. The clips 22 are for the purpose of receiving the ends of conductors. A convenient way of attaching the conductors to the clips is to provide the latter with a grooved extension 23 adapted to receive the stripped end 24 of a conductor. By simply bending 75 the sides of extension 23 over the conductor (see Figs. 3 and 4), the latter is securely connected to the clip and the associated socket contact.

The four conductors 25, 26, 27 and 28 are 80 connected, respectively, to socket contacts 14, 15, 16 and 17, which are in position to be engaged by the terminal pins of a vacuum tube. We may assume that contact 14 connects with the positive side of the filament, 85 contact 15 with the negative side of the filament, contact 16 with the grid, and contact 17 with the plate. As seen in Fig. 3, the connecting clips 22 extend toward the openings 4 in the socket base B, thus making it 90 easy to insert the conductors into the shallow recess of the base for connection with the clips.

As previously stated, the springs prongs 12 normally assume an upward position, as 100 indicated in Fig. 5. When the vacuum tube is inserted in the socket, the terminal pins a thereof bear down on the socket contacts and depress them into the position shown in Figs. 4 and 6. This means that a good electrical contact is established between the socket contacts and the lamp. When the lamp is removed, the resilient prongs 12 snap back into normal position, due to the action of the torsional spring base of each 105 prong. Even when a lamp with longer terminal pins is used, the socket contacts return to normal position when released, because the prongs 12 will stand considerable depression or bending.

110 It is clear from the foregoing that I have provided an exceedingly simple and efficient mounting of the socket contacts to insure positive engagement at all times with the terminal pins of the inserted vacuum tube. Although I have shown the spring 11 made of a single piece of tempered steel, it is plain that in the broader aspect of my invention the spring support for the socket contacts 115 can be made in sections, so that each contact will have a spring section of its own. While such a construction would be entirely practical, it would not be as neat and simple as the one-piece spring shown in the drawings.

120 Aside from the new spring support for 125

the contacts, it will be seen that the base and shell of my new socket embody structural features of novelty which go to produce a socket of utmost simplicity and compactness.

5 By making the shell and base of metal, the socket becomes practically unbreakable.

I claim as my invention:

1. A vacuum-tube socket comprising a base, a tubular shell on said base, a unitary 10 resilient support at the bottom of said shell, and insulated contacts on said support.
2. A vacuum-tube socket comprising a base, a tubular shell on said base, four torsional spring blades of practically identical structure mounted in substantially radial position at the bottom of said shell, and insulated contacts carried by said spring blades.
3. A vacuum-tube socket comprising a base, a tubular shell on said base, a circular spring supported at the bottom of said shell substantially at diametrically opposite points, inwardly extending prongs on said spring at points intermediate between the 25 supporting points of the spring, and insulated contacts carried by said prongs.
4. A vacuum-tube socket comprising a base, a tubular shell on said base, a one-piece torsional spring at the bottom of said shell, said spring consisting of a band of resilient metal supported substantially at diametrically opposite points, integral prongs extending inwardly from said band at points intermediate between the supporting points 30 of said band, and insulated contacts carried by said prongs.
5. In a vacuum-tube socket, an annular spring having substantially radial prongs for resiliently supporting a plurality of insulated contacts.
6. In a vacuum-tube socket, an annular spring having substantially radial integral prongs for resiliently supporting a plurality of insulated contacts.
- 45 7. In a vacuum tube socket, an arc-shaped metal spring provided with an integral resilient prong extending inwardly from the inner edge thereof, and a contact on said prong.
8. In a vacuum tube socket, a one-piece torsional spring consisting of a flat arcuate band of spring metal provided with a substantially radial prong, and a contact on said prong.
- 50 9. In a vacuum-tube socket, a one-piece torsional spring consisting of a circular band provided with prongs, and insulated contacts on said prongs.
10. A vacuum-tube socket comprising a 55 base having an opening, lugs arranged to project into said opening, a tubular shell having lugs at its lower edge in alignment with the lugs on said base, fastening devices passing through the aligned lugs for securing

the shell on the base, a circular spring 65 clamped between said aligned lugs and held in place by said fastening devices, prongs on said spring intermediate between said lugs, and insulated contacts carried by said prongs.

70 11. A vacuum-tube socket comprising a base having an opening, lugs arranged to project into said opening, a tubular shell having lugs at its lower edge in alignment with the lugs on said base, fastening devices passing through the aligned lugs for securing the shell on the base, spring means held in place by said fastening devices, and insulated contacts mounted on said spring means so as to be resiliently supported 80 thereby.

12. A vacuum-tube socket comprising a one-piece sheet-metal base formed with a peripheral flange to provide a shallow recess at the bottom of the base, said flange 85 having openings at certain points for the insertion of electrical conductors, a one-piece sheet-metal shell secured on said base, a resilient support at the bottom of said shell, insulated contacts carried by said resilient 90 support, and clips connected to said contacts and extending into said recess, said clips being adapted to be connected to electrical conductors.

13. A vacuum-tube socket comprising a 95 one-piece sheet-metal base formed with a peripheral flange to provide a shallow recess at the bottom of the base, said flange having openings at certain points for the insertion of electrical conductors, a one-piece 100 sheet-metal shell secured on said base, a resilient support at the bottom of said shell, insulated contacts carried by said resilient support, and means in said recess for connecting electrical conductors to said contacts.

14. A vacuum-tube socket comprising a one-piece sheet-metal base having an opening, lugs formed on said base to project into said opening, a one-piece sheet-metal shell 110 having lugs at its lower edge in alignment with the lugs on the base, fastening devices passing through said aligned lugs, a resilient support at the bottom of said shell, and insulated contacts carried by said resilient 115 support.

15. A vacuum-tube socket comprising a one-piece sheet-metal base having an opening, lugs formed to project into said opening, a one-piece sheet-metal shell having lugs at its lower edge in alignment with the lugs on the base, fastening devices passing through said aligned lugs, a one-piece torsional spring secured to said lugs, and insulated contacts carried by said spring.

16. As a new article of manufacture for resiliently supporting the contacts of a vacuum-tube socket, a one-piece metal

spring consisting of a substantially circular body provided with inwardly extending prongs.

17. As a new article of manufacture for resiliently supporting the contacts of a vacuum-tube socket, a one-piece metal spring consisting of a substantially circular body provided with four inwardly extending prongs arranged substantially at diametrically opposite points.

18. In a vacuum-tube socket, a circular band of spring metal fastened at a plurality of points, prongs extending inwardly from said spring band at points intermediate said fastening points, whereby each prong is resiliently supported by a section of said spring band, and a contact on each prong.

19. In a vacuum-tube socket, a circular band of spring metal fastened at a plurality of points and provided intermediate said points with integral prongs extending inwardly from the inner edge of said band, whereby the free portions of said band between the points of attachment constitute torsional spring supports for said prongs and a contact on each prong.

20. As a new article of manufacture for resiliently supporting the contacts of a vacuum-tube socket, a one-piece sheet metal spring consisting of a substantially circular band provided with prongs extending inwardly from the inner edge of said band.

STANLEY D. LIVINGSTON.
